UNITED STATES PATENT OFFICE.

OSCAR A. SMITH, OF CLEVELAND, OHIO, ASSIGNOR TO EDWIN C. HENN, OF CLEVELAND, OHIO.

NUT-TAPPING MACHINE.

No. 899,915.

Specification of Letters Patent. Patented Sept. 29, 1908.

Application filed August 24, 1906. Serial No. 331,825.

To all whom it may concern:

Be it known that I, OSCAR A. SMITH, a citizen of the United States, residing in Cleveland, in the county of Cuyahoga and 5 State of Ohio, have invented certain new and useful Improvements in Nut-Tapping Machines, of which the following is a specification.

This invention relates to machine tools 10 used for cutting threads in the bores of nut-blanks or other members, and known as nut-tapping machines.

The object of the invention is to provide a machine whereby a series of nuts or nut-blanks or other members are successively brought to a certain part of a magazine or other member; and while rigidly held in such position are threaded by means of a tapping tool; in which machine the successive nut-blanks are tapped from opposite sides. That is, the tap-member enters the bore of one nut from the right hand side while the succeeding nut has the tap enter its bore from the left hand side.

25 In another application filed by me on the 16th day of August, 1906, Serial No. 330,894, is shown and claimed the form of tap-member used in the present invention, which is in the nature of a double-end reversible tap; 30 that is, the tap can be passed entirely through the bore of the nut-blank to cut a thread therein, and then can be passed through another nut in the opposite spiral direction, and operated entirely through the 35 second member; the thread cut in both the nut-blanks being identical.

It is an object of the present invention to provide an automatic machine for operating this reversible tap, whereby it is passed into 40 and through a nut-blank from one end, and upon another nut-blank being placed in the same position, the tap is moved endwise in the opposite direction to thread the second blank. And so on, each back and forth 45 movement of the tap causing the same thread to be cut in the successive blanks.

In the accompanying drawings, representing one embodiment of my invention, Figure 1 shows a front elevation; Fig. 2 is an end 50 elevation; Fig. 3 is a detail view in elevation and section, showing one of the socket-spindles for operating the tap; Fig. 4 is an end view of the latter spindle; Figs. 5, 6 and 7 show the tap with its operating spindles and a magazine for the nut-blanks, the tap and spindles being in successive positions;

Fig. 8 is a vertical section through the magazine, showing its mechanism for feeding the nut-blanks successively; and Fig. 9 is a view of the tap.

The special form of tap that the machine is designed to operate has the cutter portion *a* located at the intermediate part of a shank *b*, the teeth being fully formed at the middle portion of the cutter, but reduced ⁶⁵ towards each end of the shank, instead of toward one end as in the usual construction. These teeth at one end are given the usual backward rake or inclination, but the rake at one end portion is in the opposite direction ⁷⁰ circumferentially from those at the other end. This is for the reason that when one end of the tap is inserted, the cutting teeth adjacent that end will have the usual negative rake to commence cutting the threads in ⁷⁵ the nut. The tap having passed entirely through the nut, is operated endwise in the opposite direction for the next blank. But, obviously, the tap ⁸⁰ must now be rotated in the opposite direction, since the thread cut will now be the same as in the previous blank. Therefore, the direction of rotation being reversed, the direction of the rake or inclination of the cutting teeth adjacent this end must be reversed.

The machine comprises essentially two operating spindles that engage the opposite ends of the tap-shank respectively, and a magazine or holder, denoted generally by *M*, whereby the nut-blanks can be successively ⁹⁰ fed to a certain position, and rigidly held in such position while being engaged by the tap. The tap is engaged by one spindle and passed into the nut, by rotating the spindle at the same time advancing it; in other ⁹⁵ words, giving it a spiral movement. Upon the tap passing partly through the nut-blank, as indicated in Fig. 6, its emerging end is engaged by the spindle member on the opposite side, which obviously must rotate ¹⁰⁰ at the same speed. The threads partially cut in the nut-blank will of themselves advance the tap, moving it into the second spindle socket. Thereupon, the first spindle upon approaching the nut, will cease its advance, while the other spindle must retreat while rotating; that is, must move spirally away from the magazine. Upon the thread portion of the tap disengaging the nut, the second spindle will continue the advance of the tap, thereby causing it to travel entirely ¹⁰⁵ through the nut-blank. At this stage the

tapped blank is ejected, and the succeeding blank fed to and locked in the same position. The second spindle now has its movement arrested and reversed to travel in the opposite rotative and advancing direction; that is, is moved in an opposite spiral direction. This will carry the end that has just moved out of the last blank, first into the next blank, and the opposite end of the cutter portion will first engage the nut-blank to start the thread in its bore. The continued rotary movement of the spindle, together with the advancing motion caused by the threads of the cutter and nut-blank, will carry the tap on through the second blank. Upon its entering end passing through the nut-blank it is engaged by the first spindle, that will now be given a spiral movement corresponding to that of the operating spindle. Upon the tap passing further through the blank, the second spindle will be arrested in its advancing movement, and the first spindle will retreat, carrying the tap entirely through the second blank and free thereof. Thereupon this nut-blank is ejected and the succeeding one placed in tapping position. The cycle of operations is now repeated as described, each succeeding nut-blank being tapped from opposite sides, but obviously the same identical thread is formed in each nut.

In the construction shown, on a suitable frame-work F are mounted spindles 2 and 3, one at each end of the machine, that are in alinement. These spindles are carried in one or more bearings 4 and 5 at each end, the spindles being endwise movable in the bearings as well as rotatable. Suitable means are provided whereby each spindle is rotated throughout its range of endwise movement. In the form shown, each spindle carries a gear 6 meshing with an elongated pinion 7, the gear 6 remaining in mesh therewith throughout its endwise movement. The two pinions 7 are fast on a shaft 8, extending from end to end of the machine, and driven by a pulley 9 fast thereon. Idle pulleys 10 and 11 are loose on the shaft on opposite sides of the pulley 9, to which reversing belts 12 and 13 are shifted, whereby the motion of the shaft 8 is reversed in the usual manner from two oppositely moving belts.

Each of the spindles is provided with means for engaging and disengaging the tap to rotate it and at the same time advance the tap. As shown, each spindle is provided with a socket member 14, shown separately in Figs. 3 and 4. This socket member is provided with a bore 15 fitting the shank of the tap, with reduced portions 16 on opposite sides of the socket, engaging flat portions on the tap-shank, to prevent rotation of the tap in the socket. By means of the main shaft 8 the two spindles will be simultane-

ously revolved and their motion reversed. The spiral motion of the spindles and sockets is, in the present construction, effected by means of cam-straps. A shaft 17 is rotatable on the frame, preferably at its lower part, and driven by a pulley 18 fast thereon, from a belt 19, running on any suitable counter-shaft, not shown. On the shaft 17, near one end of the machine, is secured a drum 20, provided with cam-straps 21 and 22. A lever 23 is pivoted on the machine bed and has a forked end 24 engaging opposite sides of a disk 25 on the spindle 2. The lower end of the lever is engaged by the cam-straps 21 and 22. These straps are so designed and located on the drum that the spindle will first be advanced in one direction, then allowed to rotate in such position without advancing, and then moved back in its former position. Near the other end of the shaft 17 is a similar drum 26, provided with strap-cams 27 and 28, that alternately engage the lower end of a lever 29 pivoted on the machine bed. This lever has a forked end 30 engaging a disk 31 on the spindle 3. By this means the spindle 3 is alternately moved in opposite directions, similar to the operation of the spindle 2.

Means are provided whereby the revolution of the driving shaft 8, and hence that of the two spindles, is reversed at the proper time when the tap has passed entirely through one blank and another is presented for tapping. This means is preferably controlled by the shaft 17 and timed relative to the position of the cam-straps on the controlling drums. In the construction illustrated, a drum 32 is fast on one end of the shaft 17, near the nest of pulleys operating the shaft 8. The drum is provided with a cam groove 33 in its periphery, whose walls engage one end of a belt-shifter lever 34. By this means, when the cam-straps have shifted the spindles to one end, the belt-shifter is operated to shift the driving belt to the idle pulley and bring the other belt on to the driving pulley, thereby reversing the spindles.

The nut-blanks in the construction disclosed, are fed through a magazine or tube 40, whose bore is such that the nuts can slide down through the magazine, but are prevented from rotating therein or having any movement except to advance. The nuts are retained in operative position by means of a lever 41 pivoted at 42 on the magazine, and having a bent arm 43 arranged to engage the two lower sides of the nut-blank; thereby retaining the blank in position for threading. The other end 44 of the lever, upon being rocked to cause the end 43 to move out of the tube and free the nut, will engage the lower side of the succeeding nut and prevent its advancement until the first nut has been removed. Should this tapped

nut not fall by gravity, the arm 44 in moving into position to engage the underside of a succeeding nut blank will strike the upper or rear side of the tapped or finished nut and 5 start its downward movement. Upon the return movement of the lever, the arm 43 is in position to arrest the downward movement of the next nut-blank as soon as the arm 44 releases the blank, permitting it to advance. 10 Suitable means are provided for rocking the arm 41. It is shown as having a slotted arm 45 that is engaged by a slide 46 movable in a block 47. The slide 46 is controlled by a cam 48 that is operated from any convenient part 15 of the machine. The cam engages a roller 49 on the lower end of the slide.

In the operation of the machine the tap engaged by one of the spindles, as spindle 3, is moved to the right while rotating, to engage the positioned nut-blank. As the tap advances through the same, the second spindle 2 is moved in the opposite direction to receive the end of the tap as it passes through the blank. The spindles being constantly rotated in the same direction and at the same speed, they will have the tap-engaging portions always in the same relative position. The emerging end of the tap will therefore enter the socket of the second spindle and properly engage its flattened portions therein. At this period the advance of the first spindle will be arrested, while the second spindle will begin to retreat. The threads started in the nut-blank will have 35 the effect of continuing the endwise movement of the tap and prevent the tap moving endwise in the second spindle socket. The retreat of the second spindle will continue and the tap will be passed entirely through 40 the nut, as shown in Fig. 7. As soon as the tap is disengaged from the first spindle, this spindle is caused to retreat to its former position. The tapped blank is now ejected and a succeeding one locked in the same position. The straps on the operating drum now cause the second spindle to advance, and the end of the tap that just passed out of the last blank, is moved into the now positioned blank. But the belt-shifter has operated to 45 reverse the driving shaft 8, and hence the rotation of the spindles, and the tap now moves in the opposite direction into the nut-blank. At this stage the first spindle is again caused to approach the magazine, and 50 as soon as the tap begins to pass through the bore of the nut-blank its end is engaged by the socket of the first spindle. The latter spindle now begins to retreat, and as soon as the second spindle reaches the magazine, its 55 forward movement is arrested, and the tap carried on entirely free of the nut and magazine, as indicated in Fig. 5. It is not necessary, so far as the tap is concerned, that the spindle on the opposite side from the tap be 60 caused to retreat and then approach the

magazine again, but this follows as a necessary consequence, as at each rotation of the operating shaft 17, the spindles must be given a complete reciprocation.

I claim as my invention:

1. In combination with a double-ended tool effective to cut the same from either end, of a pair of opposed tool holding means for engaging the tool at its opposite ends alternately and at each side of a blank, and means for rotating and advancing each of said tool holding means thereby to cut successive blanks first from one side and then from the other. 70

2. In a nut-tapping machine, the combination with a reversible double end tap, of a work-holder for holding the article in a certain predetermined position, means for alternately engaging the tap by its opposite ends to pass the tap entirely through the articles successively in opposite directions, and means for alternately advancing said means and thereby the tap in opposite directions and for rotating it during such advance. 80

3. In a nut-tapping machine, the combination with a double end reversible tap, of a pair of alining spindles having tap-engaging portions at their opposing ends organized to engage and rotate the tap, means for causing endwise movement of the spindles and timed so that said tap will be released and one spindle withdrawn from said tap at a predetermined period, means for rotating the spindles in the several positions of endwise movement, and means for reversing the rotation of the spindles. 90

4. In a nut-tapping machine, the combination with a double end reversible tap, of a pair of alining spindles provided with socket portions on their opposing ends for engagement with the tap ends to rotate the same, the spindles being supported for rotation and also for endwise movement, a shaft, means for rotating the spindles in their several positions of endwise movement from the shaft, means for driving the shaft alternately in opposite directions, means for causing endwise movement of the spindles during rotation and timed so that said tap will be released and one spindle withdrawn from said tap at a predetermined period. 105

5. In a nut-tapping machine, the combination with a double end reversible tap, of a pair of spindles rotatably supported in alinement, the spindles being provided with socket portions on their opposing ends formed to fit the tap ends to rotate the same, a driving shaft adjacent the spindles and provided with elongated pinions at each end, a gear on each of the spindles engaging one of said pinions, whereby the spindles are rotated in their several positions of endwise adjustment, a second shaft provided with a pair of drums carrying cam-straps, each of 120 125 130

the spindles being provided with a disk portion, levers pivoted on the machine and having forked portions engaging said disks respectively, each lever being engaged by said 5 cam-straps on one drum, whereby the levers are oscillated to shift the spindles endwise, said cam straps being so positioned that the tap will be released and one spindle withdrawn from said tap at a predetermined period, and means operated from the second shaft for reversing the movement of the driving shaft.

6. In a nut-tapping machine, the combination with a double end reversible tap, of a 15 pair of spindles rotatably supported in alignment, the spindles being provided with socket portions on their opposing ends formed to fit the tap ends to rotate the same, a driving shaft adjacent the spindles and provided 20 with elongated pinions at each end, a gear on each of the spindles engaging one of said pinions, whereby the spindles are rotated in their several positions of endwise adjustment, a second shaft provided with a 25 pair of drums carrying cam-straps, each of the spindles being provided with a disk portion, levers pivoted on the machine and having forked portions engaging said disks respectively, each lever being engaged by said 30 cam straps on one drum, whereby the levers are oscillated to shift the spindles endwise, said cam straps being so positioned that the tap will be released and one spindle withdrawn from said tap at a predetermined period, means operated from the second shaft 35 for reversing the movement of the driving shaft, a magazine for nut-blanks arranged between the spindles for holding the nut-blanks in the path of movement of the tap, 40 and means operated by the machine for feeding the nuts successively to position of engagement with the tap and for ejecting the blanks when tapped.

7. In combination with a single double 45 ended tap effective to cut from either end, of duplicate tap holding means, mechanism for rotating and advancing said tap holding means, alternately to engage said double ended tap and pass it through blanks thereby 50 to thread successive blanks, first from one side and then from the other, and means for feeding blanks alternately to the ends of the tap.

8. In the machine of the class specified, 55 the combination of a pair of opposed tool holding means, mechanism for rotating and advancing said tool holding means alternately to engage by its opposite ends a double ended tool effective to cut from either 60 end thereby to pass such a tool through blanks to cut successive blanks first from one side and then from the other, said mechanism including means for rotating both of 65 said tool holding means together and at the same speed during the cutting of one blank

in one direction and during the cutting of a successive blank in the opposite direction.

9. In a machine of the class described, the combination with a double ended tool, of a 70 pair of duplicate tool holding means, each constructed to engage the opposite ends of a double ended tool effective to cut from either end, and means for operating said duplicate tool holding means thereby to pass a tool from one to the other of said tool holding 75 means and completely through blanks from one side of one and the opposite side of a successive blank and including means for rotating both of said duplicate tool holding means together and at the same speed in 80 one direction during the threading of one blank and in the opposite direction during the threading of a succeeding blank.

10. The combination of work holding means, tool holding means comprising a 85 pair of opposed tool holders constructed to engage by its opposite ends a double-ended tool effective to cut in the same manner from either end, mechanism for actuating said tool holding means so that both ends 90 of the tool will be grasped during a part of each cutting operation while such ends will also be alternately released to permit the passage of the blanks successively from opposite ends of the tool and so that the tool 95 will be passed in one direction at one time completely through a blank to cut the same and then passed backward completely through a succeeding blank to also cut the same in the same manner as the preceding 100 blank, and means for rotating one of said means in opposite directions at different times.

11. The combination of work holding means, of double-ended tap effective to cut 105 the same kind of thread from either end, a pair of opposed tap holding means each constructed to alternately engage the opposite ends of said tap, mechanism for rotating one of said means in one direction at one time and in the opposite direction at another time thereby to pass said tap completely through the means to be cut from one side of one and the opposite side of a 110 succeeding means, to cut during each such passage the same kind of thread, and means for actuating said tool holding means so that they will grasp both ends of the tap during a part of each cutting operation and will also alternately release the ends thereof 115 for the passage of successive blanks alternately from the opposite ends of such tap.

12. In a nut tapping machine, the combination with a double ended tap, of means for 120 tapping nut blanks with the same kind of thread alternately from each side and comprising a pair of spindles, means timed to effect the release of the tap from its spindle when the threading operation is finished on a blank and permit the threaded nuts to pass 125

from the tap first from one side and then from the opposite side thereof in succession, means for operating said spindles to rotate them together and at the same speed in the same direction during the threading of one blank and in the opposite direction during the threading of a succeeding blank, and means for feeding blanks to the ends of said tap alternately.

10 13. In a machine of the class described, the combination of means for successively feeding blanks into position to be worked and comprising means effective to prevent the advancement of one blank until the preceding finished blank has been removed, said means also having a part thereof effective to strike the top of the finished blank and assist in the removal of such blank.

14. In a machine of the class described, the combination of means for successively feeding blanks into position to be worked and comprising a chute and a two-part means located adjacent thereto, one part in position to engage the underside of a blank and hold it in position for cutting and the other part to engage the underside of a succeeding blank and hold it in position against advancement until the first blank is released, said last part also constructed to strike the top of the finished blank and assist in removing it.

30 15. In a machine of the class described, the combination of means for successively feeding blanks into position to be worked and in-

cluding a guideway and means effective for preventing the advancement of one blank until the preceding finished blank has been removed and also effective to assist in the removal of such finished blank, and comprising a rocking lever located adjacent to said chute and one end constructed to engage and lock a blank in position to be worked and the other end to engage a succeeding blank on the rocking of said lever and prevent the movement thereof until the removal of the finished blank and to also engage said finished blank and assist in the removal thereof.

16. In a machine of the class described, the combination of means for automatically feeding successive blanks into position to be worked and including a guideway and means effective to prevent the advancement of one blank until the preceding finished blank is removed and also effective to assist in the removal of such finished blank, and comprising a rocking lever pivoted adjacent to said chute and one end constructed to engage and lock a blank in position to be worked and the other end to engage a succeeding blank on the rocking of said lever and prevent the movement thereof until the removal of the finished blank and to also engage said finished blank and assist in the removal thereof.

OSCAR A. SMITH.
